(57) **CLAIM**

The ornamental design for a device for puncturing a skin, as shown and described.

DESCRIPTION

FIG. 1 is a front plan view of a device for puncturing a skin, showing our new design, wherein a rear plan view of the device for puncturing a skin would appear identical to FIG. 1; FIG. 2 is a right side view of the device for puncturing a skin of FIG. 1, wherein a left side view of the device for puncturing a skin would appear identical to FIG. 2;

FIG. 3 is a bottom plan view of the device for puncturing a skin of FIG. 1;

FIG. 4 is a top plan view of the device for puncturing a skin of FIG. 1;

FIG. 5 is front, left side and top perspective view of the device for puncturing a skin of FIG. 1, wherein a front right side and top perspective view of the device for puncturing a skin would appear as a mirror image of FIG. 5;

FIG. 6 is a front, right side and bottom perspective view of the device for puncturing a skin of FIG. 1, wherein a rear, right side and bottom perspective view of the device for puncturing a skin would appear as a mirror image of FIG. 6; and,

FIG. 7 is a front, left side and bottom perspective view of the device for puncturing a skin of FIG. 1, wherein a rear, left side and bottom perspective view of the device for puncturing a skin would appear as a mirror image of FIG. 7.
